CLAIM

The ornamental design for a dual pet leash, as shown and described.

DESCRIPTION

FIG. 1 is a top plan view of a dual pet leash showing my new design;

FIG. 2 is a bottom plan view thereof;

FIG. 3 is a front elevation view thereof;

FIG. 4 is a rear elevation view thereof;

FIG. 5 is a right elevation view thereof;

FIG. 6 is a left elevation view thereof; and,

FIG. 7 is an isometric view thereof.

The broken lines in FIG. 6 depict environmental subject matter only and form no part of the claimed design.
